UNITED STATES PATENT OFFICE.

ENOCH DUNKERLEY, JR., OF VILAS, PENNSYLVANIA, ASSIGNOR OF ONE-HALF TO
FREDRICK DUNKERLEY, OF ONEIDA, NEW YORK.

COMBINED SHADE AND CURTAIN BRACKET.

No. 870,848.

Specification of Letters Patent.

Patented Nov. 5, 1907.

Application filed July 20, 1906. Serial No. 327,046.

To all whom it may concern:

Be it known that I, ENOCH DUNKERLEY, Jr., a citizen of the United States, residing at Vilas, county of Lycoming, State of Pennsylvania, have invented certain new and useful Improvements in a Combined Shade and Curtain Bracket; and I do hereby declare the following to be a full, clear, and exact description of the invention, such as will enable others skilled in the art to which it appertains to make and use the same.

10 This invention relates to certain new and useful improvements in curtain and shade fixtures for windows, and has special reference to a combined fixture of this character performing the dual function of a combined curtain and shade bracket.

15 To this end the invention contemplates a simple, practical and highly efficient form of combined curtain and shade fixture, the main parts of which are stamped from a sheet of material and then folded to the desired shape.

20 It is also the purpose of this invention to provide a fixture of this type which will be adjustable and adapted to be extended to accommodate itself to any style or length of shade roller, said fixture having as an important and desirable element of its combination, laterally

25 extending arms, which when the fixture is in applied position, overlie and bear against the front face of the window casing and thereby prevent any twisting of the fixture upon said window casing. It is to be noticed that this feature of the invention is particularly a desirable one when the ends of the bracket are extended to a position beyond the sides of the window casing, in which position, if it were not for the laterally extending arms, the bracket ends would sag by reason of the weight of the shade and curtain fixings, and necessarily

35 twist the fixture out of shape.

With these and other objects in view, which will more readily appear as the nature of the invention is better understood, the same consists in the novel construction, combination, and arrangement of the parts, 40 which will hereinafter be more fully described and claimed.

The essential features of the invention provided for carrying out the objects above indicated are necessarily susceptible to structural modification without departing from the spirit and scope of the invention, but a preferred embodiment of the improvements is shown in the accompanying drawings, wherein,

Figure 1 is a perspective view of a combined curtain and shade fixture embodying the features of the present invention, the same being shown in its operative applied position upon a window casing or frame. Fig. 2 is a similar view of the fixture shown in applied position, but having the ends of the bracket extended beyond the sides of the window casing, and Fig. 3 is a view 55 of the right hand member of the bracket before the same

has been folded into its desired shape, showing how the said member may be stamped from a single blank.

In carrying out the present invention any suitable material may be utilized in the construction of the fixture, but it is preferable to employ for this purpose 60 sheet metal stampings on account of the cheapness, lightness, and durability thereof, while at the same time permitting a more convenient fitting of the parts for the purposes of adjustment.

The combination fixture as illustrated in the drawings includes in its general organization two bracket members, a right and a left hand one, adjustably connected together so as to be capable of being extended to fit any length of shade roller, and it is to be noted that in the constructing of either one of these members, the 65 same general principle is to be followed, although the positioning of the bracket members of each set necessitates the folding of the right and left hand members differently. So far as the general structure of the brackets is concerned, they could be stamped from the 70 sheet metal by means of the same die, except that the window-shade-receiving notches and apertures, and also the perforations and slot whereby the members are permitted to be adjustably connected together, would have to be formed in the bracket members subsequent 75 to the stamping of the same from the blank. However, to obviate this second handling of the blank I preferably employ two dies, one for forming one bracket member and another for forming the other member.

Referring particularly to Fig. 3, the right hand 80 bracket member, it will be noted, is illustrated as it appears stamped from a sheet of metal, 1 indicating the support-engaging portion of the same. The portion 1 is provided with a perforation 2 which receives suitable fastening means, such for instance as a screw 85 or wire nail, for the purpose of securing the bracket members in proper position upon a window casing or frame. The slot 3 is also formed in the portion 1 of the right hand bracket member, and receives the rivets 4—4, which also pass through perforations in 90 the portion 1 of the left hand bracket member as clearly shown in Figs. 2 and 3, thereby serving to loosely connect the two members together and permitting them to be capable of being adjusted to fit any 95 length of shade roller.

100 Integrally formed with the support-engaging portion 1 of each of the bracket members is a bracket arm 5, the same being provided at its extreme outer end with a recess or notch 6 for receiving the curtain pole and supporting the same securely in place. It is also to 105 be observed that a notch 7 is formed in the right hand bracket arm for the receiving of one end of the window shade and that an aperture 8 is formed in the left hand bracket arm into which the opposite end of the shade roller is to be positioned. Integral with the bracket 110

arms 5 are suitable brace arms or pieces 9 and 10 which extend below the bracket arm 5 and serve to strengthen this part of the fixture. The brace arm 9 is arranged vertically when the fixture is in applied position, and 5 the brace arm 10 extends below the bracket arm 5 from the extreme outer end thereof at an angle of about 45 degrees, and meets the vertically arranged brace arm at a point indicated at 11, where it is integrally formed therewith. At this point is integrally 10 formed as a part of the bracket blank the arm 12, which arm is parallel with the support-engaging portion 1 and arranged directly below said portion. These arms 11, one on each of the bracket members, extend 15 in a lateral direction from the ends of the bracket brace arms toward each other when in applied position, and at all times bear against the front face of the window casing or frame.

As is often found to be the case, the window frame is of less width than the length of the shade roller, and 20 it therefore becomes necessary to extend the bracket ends beyond the sides of the window casing to accommodate the shade roller, or else cut the shade and roller down to a size to fit the window, which takes time and also prevents the shade from being used at a wider 25 window in the future. In extensible brackets heretofore known, no provision is made for preventing the bracket ends from sagging when the said ends are extended beyond the sides of the window casing as above stated. In the present invention, this is provided for by having the laterally extending arms 11, which bear against the front face of the window casing 30 and thereby support the bracket ends in all of their adjusted positions and prevent any twisting of the fixture upon the window casing.

35 As has been stated the right and left hand bracket members are quite similar in construction, they only differing in certain minor details, and they are stamped

out of sheet metal into a shape substantially as shown in Fig. 3, after which they are folded into proper shape at the places indicated by dotted lines in this figure. 40

From the foregoing it is thought that the construction, use and many advantages of the herein described combination fixture will be readily apparent without further description, and it will also be understood that changes in form, proportion, and minor details of construction may be resorted to without departing from the spirit of the invention or sacrificing any of the advantages thereof. 45

What I claim is:—

1. A window fixture, comprising two bracket members 50 adjustably connected together and adapted to be secured to the window frame or casing, and a horizontally extending arm projecting inwardly from each bracket member and adapted to overlie and bear against the face of the window casing at a point below said bracket members, 55 said arms being of sufficient length to serve as a brace or support for the bracket ends in whatever position they occupy when extended beyond the sides of the window casing.

2. A window fixture consisting of two bracket members 60 adjustably connected together and adapted to be secured to the window frame or casing, said bracket members comprising in each instance a support-engaging portion, a bracket arm extending at an angle from the support-engaging portion, and a horizontally extending arm connected to the bracket arm at the lower end thereof and adapted to overlie and bear against the front face of the window casing, said arms lying in the same vertical plane with the support-engaging portion and being of sufficient length to serve as a brace or support for the bracket arms 65 in whatever position they occupy when extended beyond the sides of the window casing. 70

In testimony whereof I affix my signature, in presence of two witnesses.

ENOCH DUNKERLEY, JR.
